UNITED STATES PATENT OFFICE.

ERASTUS M. KINNE, OF CUBA, NEW YORK.

COCKEYE.

SPECIFICATION forming part of Letters Patent No. 227,904, dated May 25, 1880.

Application filed January 15, 1879.

To all whom it may concern:

Be it known that I, ERASTUS M. KINNE, of Cuba, in the county of Allegany and State of New York, have invented certain new and useful Improvements in Cockeyes; and I do hereby declare the following to be a full, clear, and exact description of the invention, such as will enable others skilled in the art to which it pertains to make and use it, reference being had to the accompanying drawings, which form part of this specification.

My invention relates to an improvement in cockeyes; and it consists in forming a hook upon one side of the cockeye, so that it can be readily attached to the harness when not fastened to the single-tree, and thus dispense with trace-carriers, as will be more fully described hereinafter.

The accompanying drawings represent my invention. Figure 1 represents it detached from the harness. Fig. 2 represents it attached to the harness.

a represents an ordinary cockeye, which has the hook c formed on one side, either in the form here shown or any other that may be preferred. By means of this hook the cockeye may be readily attached to a ring in the harness, and thus support the trace when the cockeye is not fastened to the single-tree, and thereby dispense with the usual trace-carriers.

This hook adds no appreciable expense to the cockeye, and does enable the traces to be quickly suspended out of the way as soon as unfastened without the help of any other device.

Having thus described my invention, I claim—

A cockeye having a hook, c, formed on it, substantially as shown.

In testimony that I claim the foregoing I have hereunto set my hand and seal this 13th day of January, 1879.
